CLAIM

The ornamental design for an ice hockey stick end cap, as shown and described in FIGS. 1-14.

DESCRIPTION

FIG. 1 is a perspective view of the ice hockey stick end cap according to an embodiment of the present design.

FIG. 2 is a right-side view of the ice hockey stick end cap of FIG. 1.

FIG. 3 is a left-side view of the ice hockey stick end cap of FIGS. 1-2.

FIG. 4 is a bottom view of the ice hockey stick end cap of FIGS. 1-3.

FIG. 5 is a top view of the ice hockey stick end cap of FIGS. 1-4.

FIG. 6 is a front-side view of the ice hockey stick end cap of FIGS. 1-5.

FIG. 7 is a rear-side view of the ice hockey stick end cap of FIGS. 1-6.

FIG. 8 is a perspective view of the ice hockey stick end cap according to another embodiment of the present design.

FIG. 9 is a right-side view of the ice hockey stick end cap of FIG. 8.

FIG. 10 is a left-side view of the ice hockey stick end cap of FIGS. 8-9.

FIG. 11 is a bottom view of the ice hockey stick end cap of FIGS. 8-10.

FIG. 12 is a top view of the ice hockey stick end cap of FIGS. 8-11.

FIG. 13 is a front-side view of the ice hockey stick end cap of FIGS. 8-12; and,

FIG. 14 is a rear-side view of the ice hockey stick end cap of FIGS. 8-13.

The present design is a pentagonal end cap for an ice hockey stick.
